(57) CLAIM

The ornamental design for a cosmetic container, as shown and described.

DESCRIPTION

FIG. 1 is a top perspective view of a cosmetic-container embodying our new design;

FIG. 2 is a bottom perspective view of the cosmetic container of FIG. 1;

FIG. 3 is a front view of the cosmetic container of FIG. 1; a rear view, a left side view and a right side view of the cosmetic container of FIG. 1 being same as the front view of the cosmetic container of FIG. 3;

FIG. 4 is an enlarged top view of the cosmetic container of FIG. 1;

FIG. 5 is an enlarged bottom view of the cosmetic container of FIG. 1;

FIG. 6 is a top perspective view of the cosmetic container of FIG. 1 with a cap thereon removed; and,

FIG. 7 is a front side view of the cosmetic container of FIG. 1 with a cap thereon removed.

The broken lines in the drawings depict portions of the cosmetic container and environmental structure, specifically the cosmetic product itself in FIGS. 6 and 7, that form no part of the claimed design.
